United States Patent Office.

JOSHUA S. SHAFFER, OF PLYMOUTH, MICHIGAN.

Letters Patent No. 63,657, dated April 9, 1867.

IMPROVEMENT IN LAND-ROLLERS.

The Schedule referred to in these Letters Patent and making part of the same.

TO ALL WHOM IT MAY CONCERN:

Be it known that I, JOSHUA S. SHAFFER, of Plymouth, in the county of Wayne, and in the State of Michigan, have invented certain new and useful improvements in "Land-Rollers;" and do hereby declare that the following is a full, clear, and exact description thereof, reference being had to the accompanying drawings, and to the letters of reference marked thereon.

In the annexed drawings, making part of this specification, B B represent two square frames, which have one common end piece, A, to which they are both hinged, as seen at G G. Within these frames are rollers, C C. Each roller has two centre pins in its ends. The pins in the outer ends of these rollers work in suitable bearings in the end pieces of the frames B B, while the pins in their inner ends work in bearings in the common end piece A. D D represent braces, which run from the outer ends of the frames B B to the centre or common end piece A. E represents the tongue or pole of the roller, which is secured to the piece A; and F represents the double-trees, to which power is attached for drawing the roller. By hinging the two frames to a common end piece and having the shafts or pins of the rollers upon which they revolve play in this end piece, a flexible roller is formed which will accommodate itself to the inequalities of ground which it may be used upon.

Having thus fully described my invention, what I claim as new, and desire to secure by Letters Patent, is—

Hinging the frames B B to the common end piece A, in which end piece the rollers C C have their bearings, for the purpose of making a flexible roller, substantially as specified.

In testimony that I claim the foregoing I have hereunto set my hand and seal this 30th day of January, 1867.

JOSHUA S. SHAFFER.
